Primary Examiner — Martie K Holtje(74) *Attorney, Agent, or Firm* — Wilson Sonsini Goodrich & Rosati(57) **CLAIM**

The ornamental design for a multispace parking pay station, as shown and described.

DESCRIPTION

FIG. 1 is a top front perspective view of a multispace parking pay station, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The multispace parking pay station housing, depicted by broken lines, has been shown for the purpose of illustrating environment that forms no part of the claimed design.

The circles depicted by broken lines in FIG. 7 have been shown for the purpose of illustrating elements that form no part of the claimed design.

1 Claim, 7 Drawing Sheets(56)
